The ornamental design for a rear view vision system for bicycles and the like, as shown and described.

DESCRIPTION

FIG. 1 is a perspective view of my rear view vision system for bicycles and the like with a camera and display device in a first embodiment;

FIG. 2 is a front view of the display device in the embodiment of FIG. 1;

FIG. 3 is a top view of the display device in the embodiment of FIG. 1;

FIG. 4 is a bottom view of the display device in the embodiment of FIG. 1;

FIG. 5 is a right side view of the display device in the embodiment of FIG. 1;

FIG. 6 is a left side view of the display device in the embodiment of FIG. 1;

FIG. 7 is a rear view of the display device in the embodiment of FIG. 1;

FIG. 8 is a front view of the camera in the embodiment of FIG. 1;

FIG. 9 is a top view of the camera in the embodiment of FIG. 1;

FIG. 10 is a bottom view of the camera in the embodiment of FIG. 1;

FIG. 11 is a right side view of the camera in the embodiment of FIG. 1;

FIG. 12 is a left side view of the camera in the embodiment of FIG. 1;

FIG. 13 is a rear view of the camera in the embodiment of FIG. 1;

FIG. 14 is a perspective view of my rear view vision system for bicycles and the like in a second embodiment utilizing the same display device as in the first embodiment;

FIG. 15 is a front view of the camera in the embodiment of FIG. 14;

FIG. 16 is a top view of the camera in the embodiment of FIG. 14;

FIG. 17 is a bottom view of the camera in the embodiment of FIG. 14;

FIG. 18 is a right side view of the camera in the embodiment of FIG. 14;

FIG. 19 is a left side view of the camera in the embodiment of FIG. 14; and,

FIG. 20 is a rear view of the camera in the embodiment of FIG. 14.
